UNITED STATES PATENT OFFICE.

SIG SCISOREK, OF NEWARK, NEW JERSEY.

TACK.

Application filed October 6, 1922. Serial No. 592,792.

To all whom it may concern:

Be it known that I, SIG SCISOREK, a citizen of the United States, residing at Newark, in the county of Essex and State of New Jersey, have invented new and useful Improvements in Tacks, of which the following is a specification.

This invention relates to improvements in thumb tacks and has for an object the provision of means whereby the tack may be lifted from the drawing board without inserting a knife or other sharp instrument beneath the tack edge with a possibility of mutilating or defacing the drawing paper.

Another object of the invention is the provision of a thumb tack having a knife edge, which will practically prohibit the insertion of a knife thereunder and which in addition, will cause the T-square or angle to ride over the head of the tack and prevent mutilating or nicking the squared edge and reduce the danger of blurring the drawing, should the square or angle strike the tack edge and accidentally contact the wet lines of the drawing, as frequently occurs with the use of an ordinary tack.

With the above and other objects in view, the invention further includes the following novel features and details of construction, to be hereinafter more fully described, illustrated in the accompanying drawings and pointed out in the appended claims.

In the drawings:—

Figure 1 is a plan view showing one form of tack.

Figure 2 is a sectional view of the same showing the use of the tack.

Figure 3 is a plan view of a modified form of tack.

Referring in detail to the drawings, wherein like characters of reference denote corresponding parts, the reference character 10 indicates the head of a thumb tack, whose shank is shown at 11. The head 10 has its greatest thickness disposed centrally and tapers outwardly to a knife-like edge 12, the said edge closely engaging the paper so as to cause the contacting T-square or angle to ride thereover without injury to the edge of the instrument. This prevents an accidental pivoting of the instrument against the edge of the tack, as frequently occurs with the use of the ordinary thick edged tack, so that liability of blurring or smearing the lines of

the drawing from this cause is prevented. 55 In addition, the formation of the knife edge 12 renders it practically impossible to insert a knife or similar sharp instrument beneath the tack edge when it is desired to remove the tack, so that mutilation or injury to the surface of the paper is also prevented. 60

For the purpose of facilitating the removal of a tack, the head 10 as shown in Figure 1 of the drawings, is provided upon opposite sides of its center with oppositely disposed arcuate slots 13 which extend entirely through the head of the tack and provide means for the insertion of finger nails whereby the tack may be conveniently lifted. The head of the tack is thicker at its center 70 than elsewhere and the inner walls 13^a of the slots 13 are inclined downwardly and inwardly toward the shank 11. This causes the edges 13^b of the aforesaid walls 13^a to be so positioned with respect to the edges 13^c 75 of the adjacent walls 13^d of said slots 13 that the finger nails are guided into the slots and in proper engagement with the walls 13^a. Through this construction, taken with the fact that the slots conform with the curvature of the nails enables firm purchase of the nails against the head of the tack and quick removal of the latter when desired. 80

The tack shown in Figure 3 of the drawings is similar in all respects to the tack just described, except that the slots 14 which extend through the head upon opposite sides of the center are arranged in parallelism.

The invention herein described and shown in the accompanying drawings provides a 90 tack which is simple in construction, convenient and efficient in use and which may be manufactured at a relatively small cost.

In addition to eliminating danger of blurring the lines of the drawing, due to the apex 95 of a triangle striking the edge of an ordinary tack, and the shank of the tack is made relatively small and thin, so that the tendency is to push the tack in as the angle or square rides over the top of the tack, instead 100 of pushing it out through contact with the edge of an angle or square with the edge of the ordinary tack head. The hole made by the tack in the drawing is thus materially reduced in size. 105

The invention is susceptible of various changes in its form, proportions and minor details of construction and the right is

herein reserved to make such changes as properly fall within the scope of the appended claim.

Having described the invention what is claimed is:—

A thumb tack having a plano-convex head provided with a relatively thick central por-

tion tapering outwardly to define a knife edge and having slots upon opposite sides of the central portion, said slots extending entirely through the head, and having downwardly and inwardly tapered walls.

In testimony whereof I affix my signature.

SIG SCISOREK.
